(57) **CLAIM**

The ornamental design for a vent of a camera body as shown and described.

DESCRIPTION

FIG. 1 is a rear, left, top perspective view of a vent of a camera body, showing my new design;

FIG. 2 is a rear, right, top perspective view thereof;

FIG. 3 is a top elevational view thereof; and,

FIG. 4 is a bottom elevational view of the vent of the camera body without environment.

The dash-dot-dash lines depict boundaries of the vent of the camera body that form no part of the claimed design.

The dashed lines depict environmental structure and form no part of the claimed design.

1 Claim, 4 Drawing Sheets
